UNITED STATES PATENT OFFICE.

ROY LINDEN HILL AND ARCHIBALD J. STRANE, OF TAMAQUA, PENNSYLVANIA,
ASSIGNORS TO ATLAS POWDER COMPANY, OF WILMINGTON, DELAWARE, A
CORPORATION OF DELAWARE.

EXPLOSIVE MIXTURE.

1,299,942.

Specification of Letters Patent.

Patented Apr. 8, 1919.

No Drawing.

Application filed November 1, 1918. Serial No. 260,697.

To all whom it may concern:

Be it known that we, ROY LINDEN HILL and ARCHIBALD JACKSON STRANE, citizens of the United States of America, residing at 5 Tamaqua, in the county of Schuylkill and State of Pennsylvania, have invented certain new and useful Improvements in Explosive Mixtures, of which the following is a specification.

10 This invention relates to certain explosive mixtures and it has for its object to prevent such explosive mixtures from becoming hard or "set," with the resultant deleterious effects.

15 Explosives consisting essentially of an organic nitrate or a mixture of organic nitrates, such as glycerin trinitrate, starch nitrate, glycol nitrates, and ammonium nitrate, but with other materials such as sodium or potassium nitrates and combustible absorbents frequently added, have, in recent years, come into extended use. These explosives, as compared with straight nitro-glycerin dynamites, while possessing the advantage of lower cost and greater safety in 20 handling, possess the very great disadvantage that they frequently become very hard in storage, even though they may not be frozen. There are several degrees of this 25 condition, from increased firmness to the hardness of frozen dynamite. This condition may lead to difficulties in inserting exploders and in charging into bore holes and to possibilities of failure to detonate, incomplete detonation, or burning in the bore hole. All of these conditions lead to decreased 30 safety and the latter three to the probability of inefficient work and poisonous fumes.

We have found that we can prevent such 35 explosives from becoming hard or "set" by introducing into their composition certain amounts of copper sulfate from which the water of crystallization has been partially or completely removed. The amount of copper 40 sulfate employed preferably ranges from five-tenths to ten per cent. The copper sulfate may be added to any ingredient of the explosives individually or to any mixture of ingredients which go to make up the finished 45 explosives. We prefer to add it after all 50 of the other ingredients of the explosives have been partially mixed.

The following composition is illustrative of an embodiment of the invention though it is apparent that the copper sulfate may be 55 advantageously employed for the purpose of preventing hardening of the mixture, in many other similar compositions.

Nitro glycerin (glycerin trinitrate)	21 per cent.	60
Ammonium nitrate	26 per cent.	
Sodium nitrate	35 per cent.	
Wood meal	14 per cent.	
Copper sulfate	3 per cent.	65
Chalk	1 per cent.	

Having thus clearly set forth the essential features of our invention and shown by example how the same may be applied, what we claim and desire to secure by Letters 70 Patent of the United States is:—

1. The addition of copper sulfate, from which the water of crystallization has been partially or completely removed, to explosives which are made up, in part or completely, of ammonium nitrate and an organic nitrate, to prevent the explosives from becoming hard or "set," unless frozen. 75

2. The addition of copper sulfate from which the water of crystallization has been wholly or partially removed to an explosive mixture containing ammonium nitrate and an organic nitrate. 80

3. The addition of five-tenths per cent. to ten per cent. copper sulfate from which the water of crystallization has been wholly or partially removed to explosives containing ammonium nitrate and an organic nitrate. 85

4. The addition of five-tenths per cent. to ten per cent. copper sulfate, from which the water of crystallization has been partially or completely removed, to explosives which are made up, in part or completely, of ammonium nitrate and an organic nitrate in order to prevent the explosives from becoming 90 hard or "set," unless frozen.

In testimony whereof we affix our signatures in the presence of two witnesses.

ROY LINDEN HILL.
ARCHIBALD J. STRANE.

Witnesses:

W.M. H. WOODWELL,
HARRY J. KRAMER.
